UNITED STATES PATENT OFFICE.

WILLIAM GROVER, OF HOLYOKE, MASSACHUSETTS.

IMPROVED GAS-REGULATOR.

Specification forming part of Letters Patent No. 36,348, dated September 2, 1862.

To all whom it may concern:

Be it known that I, WILLIAM GROVER, of Holyoke, in the county of Hampden and State of Massachusetts, have invented a new and useful Improvement in Gas-Regulators; and I do hereby declare that the following is a full, clear, and exact description of the same, reference being had to the accompanying drawings, forming part of this specification, in which—

Figure 1 is a central vertical section of the regulator. Fig. 2 is a plan of the same with the cover removed to expose the interior.

Similar letters of reference indicate corresponding parts in the two figures.

To enable others skilled in the art to make and use my invention, I will proceed to describe its construction and operation.

A is the shell of the regulator, composed of a single casting open at the top and having a horizontal partition, a, which separates the inlet-chamber B from the outlet-chamber C, such partition having an opening, b, which is surrounded within the outlet-chamber C by an annular basin, c, to contain mercury, and a channel, d, being formed around the top of the said shell to form another mercury-basin.

e is the inlet-opening to the chamber B for the connection of the pipe for the introduction of the gas from the main, and f is the outlet-opening from the chamber C for the connection of the outlet for conducting the regulated flow of gas to the burners.

D is the oscillating siphon-shaped pipe, which constitutes both the means of communication between the chambers B and C and the regulating-valve. One end, h, of this pipe covers the opening b and is always immersed in the mercury in the surrounding basin c, and the other end, i, dips into a basin, g, containing mercury, supported upon the partition a. The end h of this pipe is supported on two fixed knife-edged bearings or fulcrums, j, arranged within the basin c, one on each side of the opening b, on which it is free to oscillate in such manner as to make the end i dip more or less into mercury in the basin g. The mouth i is notched all round to permit the flow of gas into the chamber C, while it dips to some extent into the basin g.

E is the inverted cup, upon the interior of

which the pressure of the gas in the chamber C acts to lift the pipe D and raise the mouth i. This cup is arranged to oscillate upon two pins, m m, which attach it by one end to the shell A, and the edges of the said cup dip into the mercury in the basin d. The said cup has rigidly attached to it two arms, k, which bear against shoulders l, provided on the pipe D near the end h, in such manner that the weight of the said cup makes it act as a lever upon the said pipe, and so tend to raise the mouth h, which, owing to the natural tendency of the weight of the said pipe, tends to descend into the basin g.

F is a movable cover fitted to the top of the shell A to cover the cup E and basin d and keep the mercury in the said cup protected from dust.

The operation of the regulator is as follows: When there is no gas entering the regulator, the weight of the cup E, causing it to act as a lever upon the pipe D, raises the mouth i of the said pipe out of the mercury in the cup g; but when gas is admitted to the chamber B it passes through the pipe D into the chamber C, and thence through the outlet f to the burners, and its pressure in the chamber C, acting upon the interior of the cup E, tends to raise the said cup, and so to draw the arms k away from the shoulders l on the oscillating pipe D and permit the said pipe to descend, and so contract the opening between its mouth i and the surface of the mercury in the basin g. According as the pressure of the gas in the chamber C is greater or less, owing to a greater or less pressure on the main or to the opening of a less or greater number of burners, it raises the cup E more or less, and so permits the pipe D to descend more or less, and thereby, more or less, contracts the opening between the mouth i of the said pipe and the surface of the mercury in the basin e, and so, more or less, reduces the supply to the chamber C, as may be required, thereby equalizing the pressure upon the burners. The notches in the mouth i of the pipe D permit the escape of gas, while the lower edge of the mouth i of the pipe dips into the mercury, and so when the pressure of the gas in the regulator is very suddenly increased prevents the sudden closing of the said mouth, and also serves to pre-

vent any flickering being produced by the oscillation of the pipe D. It may be understood from the foregoing description that the mouth *i* of the pipe D constitutes a valve whose seat is the mercury in the cup *g*.

A flexible diaphragm may be substituted for the inverted cup E and mercury-basin *d*; but I prefer the cup and basin; and a flexible pipe-connection may be substituted for the mercury-basin *c*; but I prefer the mercury-basin.

By having the fulcrums *jj* arranged within the mercury-cup *h* the free oscillation of the siphon D is always secured, as the tar and other impurities arising from the gas can never come in contact with the fulcrums.

What I claim as my invention, and desire to secure by Letters Patent, is—

1. The combination, with the oscillating pipe D and its fulcrums *jj*, of the inverted cup E and its arms *kk*, in the manner herein shown and described.

2. The arrangement of the fulcrums *jj* within the mercury-cup *h*, as herein shown and described.

WM. GROVER.
